H.W.5pear, INVENTOR.

BY

Geo. P. Kimmel. ATTORNEY.

UNITED STATES PATENT OFFICE.

HERMAN W. SHEEL, OF DECORAH, IOWA.

VENTILATING HOOD.

Application filed May 19, 1925. Serial No. 31,355.

To all whom it may concern:

Be it known that I, HERMAN W. SHEEL, a citizen of the United States, residing at Decorah, in the county of Winneshiek and State of Iowa, have invented certain new and useful Improvements in Ventilating Hoods, of which the following is a specification.

This invention relates to fume hoods of the type used in chemical laboratories.

10 The primary object of this invention is the provision, in a manner as hereinafter set forth, of a fume hood which may be located upon the work table of the chemist or chemistry student, in a handy location for use and 15 further having means for conveying any noxious fumes being evolved through passage ways leading from the hood in such a manner that they will be out of sight and out of the way.

20 Another object of the invention is the provision, in a manner as hereinafter set forth, of a fume hood so designed that it may be placed in the center of a double work table and be used from both sides, by two 25 persons, a common lead off passage way serving for both sides of the hood.

Another object of the invention is the provision, in a manner as hereinafter set forth, of means for supporting apparatus 30 needed in connection with the operation or use of a hood, or in other chemical operations.

Still another object of the invention is the provision, in a manner as hereinafter set 35 forth, of a single or double fume hood having a new and novel means for regulating the draughts therethrough.

The final object of the invention is the provision, in a manner as hereinafter set 40 forth, of a chemical fume hood of simple but strong construction, exceptionally efficient in action, and inexpensive to manufacture and set up in position.

The invention will be best understood 45 from a consideration of the following detailed description taken in connection with the accompanying drawing forming a part of this specification, with the understanding that the invention is not confined to any 50 strict conformity with the showing of the drawing but may be changed and modified so long as such changes and modifications mark no material departure from the salient features of the invention as expressed 55 in the appended claims.

In the drawing:—

Figure 1 is a front elevation of the hood embodying this invention showing clamp support rods connected thereto.

Figure 2 is a top plan view of the showing of Figure 1.

Figure 3 is a section taken upon the line 3—3 of Figure 1.

Figure 4 is a section taken upon the line 4—4 of Figure 1.

Figure 5 is a detailed sectional view showing the manner in which the clamp support rods are secured to the hood.

Referring now to the drawing in detail wherein like numerals of reference indicate corresponding parts throughout the several views, the double hood constructed in accordance with the invention comprises primarily an elongated body of metal having the edges rolled as indicated at 1 and having 70 two bends 2 transversely thereof, in spaced relation and adjacent the central portion of the body. When the body is bent at these two points there is formed two spaced parallel portions which constitute vertical sides 3 and the connecting portion 4 constitutes the top of the hood. There is thus formed an inverted substantially U-shaped member, the lower edges of the sides 3 being bent back 75 upon themselves as at 5 to provide flanged 80 edges.

The top 4 is provided along its central portion with a transversely extending series of apertures 6, the purpose of which will 85 become apparent as the description of the invention proceeds.

Secured across between the side walls 3 of the body and extending throughout the length thereof, is a series of spaced partitions, a pair of outer partitions 7 and an intermediate partition 8. These three partitions have their edges flanged as at 9, and through the side flanges of the partitions and the top flange of the inner one are passed rivets or bolts 10 through the top 95 and sides of the body as is shown and, when the body is in position upon the table 11, the bottom flanges rest upon the surface of the table.

The upper portion of each of the outer partitions 7 has cut therethrough the passage 12, and as shown clearly in Figure 4 when the flanges 9 formed along the side edges of these outer partitions are sufficiently turned to turn back the portions of the 100

flange upon itself as indicated at 13 this turned back portion extends beyond the inner side of the partition and is turned across the inner face thereof and spaced therefrom to provide the tongues 14. These tongues extend throughout the length of the inner edge of each of the outer partitions 7. Slidably held against the inner face of each of the partitions 7 by means of the tongues 14 is a gate or door 15 and secured to the upper edge of each of the gates 15 is a rod bar 16 which projects through an inner one of the openings 6 to extend beyond the top of the hood body and each of these rods has upon the upper end thereof the crown nuts 17. The spring tension exerted by the tongues 14 against the gates 16 serves to frictionally hold the gate in any desired adjusted position.

Secured across the top of said body is a reinforcing plate 18 and through each corner of this plate and through the top of the body is passed a bolt 19 the head of which engages the under surface of the top 4 while the shank extends a substantial distance above the top of the plate 18. Encircling each of the bolts 19 is a threaded collar 20 which secures the plate to the top of the hood and secured to each of the bolts 19 by the projection of the bolt through a transverse bore therethrough, is a brace rod 21. This brace rod is held securely against the collar 20 by means of the wing nut 22 which is threaded upon the bolt 19 and bears against the rod as shown in Figure 5.

These rods 21 as is shown in Figure 2 extend outwardly from the hood body at various angles and each carry thereon a double clamp 23 which is designed to grip a vertical support rod 24. With this arrangement of supporting rod 21 extending from the top of the hood body and gripping vertical rods 24 additional rigidity is given to the vertical support rods, and further conveniently located adjustable means is provided for the support of holding devices such as evaporating dish holders indicated by the numeral 5, for supporting articles within the hood. It will be readily seen that by loosening the wing nuts 22 the horizontal rods 21 can be swung as desired to position the vertical rods 24 around at one side of the hood or bring the same forward to a position in front of the hood so that holding devices such as that indicated by the numeral 25, which are clamped upon the vertical rods 24 may be more readily located within the hood. By the arrangement of a cross support, a thermometer may be so suspended as to allow the bulb thereof to extend through the outer one of the

apertures 6 to the interior of the hood for keeping a check upon the temperature therein.

When the hood embodying this invention is in position upon the table 11, it is located above an opening in the table from which opening there extends a fume lead-off pipe 26, the mouth of which is of the same size as the lower end of the compartment formed between the two outer partitions 7. Any number of these lead-off pipes 26 may be connected to a main lead-off pipe and proper suction means connected therewith to maintain a continuous draught through the open-gates 15 of the hood and through the lead-off pipes 26.

From the foregoing description it will be readily seen that there has been provided a new, novel and very efficient laboratory fume hood which may be very conveniently used in that it has no overhead lead-off pipe, and further due to its compactness, it can be located at a convenient point for the user.

I claim:

1. A fume hood of the character set forth, comprising a body having top and side walls and open front and rear, a central partition in said body, dividing the same into two portions, a pair of partitions spaced from and one on each side of said central partition to provide fume chambers at the rear of each section, each of said last mentioned partitions having an aperture through the upper part thereof, means for adjustably closing said apertures, and a fume lead-off from the lower portion of the fume chambers.

2. A double fume hood of the character set forth, comprising a body having top and side walls and open front and rear, a central partition in said body, dividing the same into two portions, a pair of partitions spaced from and one on each side of said central partition to set up in connection therewith a fume chamber at the back of each said portion, said last mentioned partitions having an aperture through the upper part thereof, and each of said free partitions having their edges turned at right angles to set up securing flanges, a spring tongue formed from the said securing flanges of said pair of partitions, a gate for said apertures frictionally held by said spring tongues, controlling means extending from said gates through the top of said body, and means for conveying fumes from the lower portions of said fume chambers.

In testimony whereof, I affix my signature hereto:

HERMAN W. SHEEL
